UNITED STATES PATENT OFFICE.

WILLIAM H. SCOTT, OF ST. LOUIS, MISSOURI.

BOLSTER.

SPECIFICATION forming part of Letters Patent No. 737,158, dated August 25, 1903.

Application filed April 23, 1903. Serial No. 153,996. (No model.)

To all whom it may concern:

Be it known that I, WILLIAM H. SCOTT, a citizen of the United States, residing at St. Louis, Missouri, have invented a certain new and useful Improvement in Bolsters, of which the following is a full, clear, and exact description, such as will enable others skilled in the art to which it appertains to make and use the same, reference being had to the accompanying drawings, forming part of this specification, in which—

Figure 1 is a top plan view, partly broken away, illustrating my invention. Fig. 2 is a side elevational view, partly broken away. Fig. 3 is an isometric perspective view showing the several parts of the head-block with compression and tension members. Fig. 4 is a sectional view on the line 4-4 of Fig. 2. Fig. 5 is a plan view of a modified form of head-block. Fig. 6 is a side elevational view of Fig. 5. Fig. 7 is a side elevational view, partly broken away, illustrating a modified form of head-block. Figs. 8, 9, 10, and 11 are detail views illustrating modified forms of the enlarged end of the tension member of my bolster; and Fig. 12 is a view in section, illustrating the manner of tying the several parts of my bolster together without the use of tie-bolts as shown in the other views.

This invention relates, broadly, to new and useful improvements in trussed bolsters, wherein the head-block is separable laterally for the purpose of permitting the introduction therein of the ends of a tension member which is held in seats in said head-blocks, and consists, in addition thereto, of certain features of detail construction and arrangement of parts, all as hereinafter more fully described, and particularly pointed out in the claims.

Referring to the drawings, 1 is a compression member, which is preferably of channel form in cross-section and may be made of a commercially-rolled channel.

2 is a tension member, which may be formed from a flat plate, as shown in the drawings, with the end portions thereof provided with any method or style of enlargement which will adapt it to coöperate with the separable head-block sections hereinafter described and be held by said head-block sections in position. In views 1 and 2 the tension member con-

sists of a flat plate continuous from end to end, upon the end portions of which are welded the stub-sections 3, which in those views are formed wider than the plate 2, whereby laterally-extending shoulders 4 are provided, adapted to interlock with inwardly-projecting shoulders 5, formed in the head-block sections. 60

In Fig. 8 the tension member is provided with a returned bent portion 4^a, flattened upon the tension member 2.

In Fig. 9 the metal of the tension member is thickened by any convenient process, as shown at 4^b, to provide a shoulder above and below the plate 2.

In Fig. 10 the metal is formed with a central opening extending laterally therethrough, a shoulder 4^c being provided above and below the plate 2. 70

In Fig. 11 the enlarged end 4^d of the plate 2 embraces a laterally-extending rod 6, which provides additional supporting means for the tension member, adapted to interlock with 75 corresponding recesses in the head-block sections.

The form of the end portion of the tension member is immaterial, and it may, if necessary, be merely a flat plate, as shown in Fig. 80 7, which is provided with rivet-openings through which the rivet 7 is projected to secure the plate 2 within the head-block sections.

The essential feature of novelty in the present bolster resides in the fact that the head-block sections are separable laterally for the purpose of taking in the ends of the tension member and when restored to their normal operative position lock therein the ends of 90 the tension member, the head-blocks being provided either with channel-recesses 8, as best shown in Fig. 3, for the flanges 9 of the channel 1 or with a laterally-projected opening through which may be extended a bolt, 95 as 10, for tying the several parts of the head-block together. 85

In the drawings at Fig. 3 the several head-block sections are shown as separately-formed castings, in which 12 represents the two main 100 castings provided with seats therein, which seats extend laterally thereof for the purpose of holding the enlarged ends of the tension member 2, while beneath the head-block sec-

tions 12 is a spring-plate 13, provided with upwardly-extended flanges 14, which flanges embrace the annular recess 15, formed at the lower edges of the blocks 12, whereby said blocks 12 are held against lateral separation, though the column-guides 16, coöperating with the columns commonly incident to railway-trucks, would hold the parts of the head-block in operative position under normal conditions without the use of the spring-plate 13.

In the modification shown at Figs. 5 and 6 flanges 17 are provided beyond the ends of the head-block sections, through which may project suitable rivets 18 for securely locking the head-block sections together, while corresponding flanges 17^a on the inner side of the head-blocks below the tension member 2 are also provided as additional securing means through which rivets may project, if desired. Thus it will be seen that by means of the head-block sections and the locking means provided it is possible to use an imperforate tension member and an imperforate compression member, or either, if desired, and in practical use no means are required to hold the parts of the bolster together, except such as are incidental to the construction of the several parts thereof. For convenience in shipping, however, bolts, such as 10, or rivets, as 18, are used to unite the several parts of the head-block sections and hold them against lateral separation. It will be observed that the bolsters illustrated in the drawings may be provided with spring-seats 13 or without such spring-seats where the head-block sections are held together by any means foreign thereto—as, for instance, the flanges 9 of the channel compression member. The spring-seats 13, with their upwardly-projecting flanges, are non-essential, and the same would be true if the compression member were reversed so that the flanges would project upwardly, provided some means, like the flanges 17 and 17^a, were provided through which securing means could be passed to hold the parts in operative position.

In addition to the features heretofore enumerated I use with my improved bolster the tie-plates 19, which are secured to the flanges 9 of the compression member by suitable rivets and extend thence downwardly below the tension member. The said tie-plates 19 are secured to the compression member at approximately the point where the side bearings are usually placed, and the object of the tie-plates 19 is to prevent buckling of the cambered compression member 1, as it has been found that under some extraordinary conditions the said compression member has a slight tendency to buckle, which would of course destroy the efficiency thereof.

For convenience in shipping the screws 20 are used to secure the spring-plate in position below the head-block sections, though it will be apparent that such securing means are not required in actual service.

I am aware that minor changes in the con-

struction, arrangement, and combination of the several parts of my device can be made and substituted for those herein shown and described without in the least departing from the nature and principle of my invention.

Having thus described my invention, what I claim as new, and desire to secure by Letters Patent, is—

1. In a bolster, a head-block composed of parts which are separable laterally; substantially as described.
2. In a bolster, a head-block composed of parts which are separable laterally and are adapted to hold the end of a tension member; substantially as described.
3. In a bolster, a head-block composed of parts which are separable laterally and are adapted to hold the enlarged end of a tension member; substantially as described.
4. In a bolster, a head-block composed of parts which are recessed for the end portion of a tension member, said parts being separable laterally; substantially as described.
5. In a bolster, a head-block composed of parts which are recessed for the enlarged end portion of a tension member, said parts being separable laterally; substantially as described.
6. In a bolster, a head-block composed of sections divided vertically; substantially as described.
7. In a bolster, a head-block composed of sections divided vertically and separable laterally; substantially as described.
8. In a bolster, a head-block composed of parts, one of which is provided with a seat, a tension member with an enlarged end adapted to be held therein and a laterally-separable part adapted to coöperate therewith; substantially as described.
9. In a bolster, a head-block composed of parts and a compression member coöperating therewith adapted to hold said parts together; substantially as described.
10. In a bolster, a head-block composed of laterally-separable parts, and a compression member coöperating therewith adapted to hold said parts together; substantially as described.
11. In a bolster, head-blocks composed of parts with recesses therein, a tension member with enlargements thereon resting in said recesses, and a compression member coöperating therewith adapted to hold said parts together; substantially as described.
12. In a bolster, a head-block composed of sections separable vertically and laterally; substantially as described.
13. In a bolster, a head-block composed of sections separable laterally, and a flanged member coöperating therewith adapted to prevent accidental separation thereof; substantially as described.
14. In a bolster, head-blocks composed of parts which are separable laterally and are provided with seats for a tension member, a tension member with enlarged end portions

- resting in said seats, a supporting member adapted to prevent lateral separation and a compression member; substantially as described.
- 5 15. In a bolster, head-blocks composed of parts which are separable laterally and are provided with seats for a tension member, a tension member with enlarged end portions resting in said seats, a supporting member adapted to prevent lateral separation and a channeled compression member; substantially as described.
- 10 16. In a bolster, head-blocks divided vertically with laterally-extended seats therein, a tension member with enlargements thereof in said seats, and a compression member provided with means for preventing lateral separation of said blocks; substantially as described.
- 15 17. In a bolster, head-blocks composed of recessed sections which are separable laterally, a tension member secured therein, and a flanged compression member coöperating therewith adapted to hold said parts in close contact; substantially as described.
- 20 18. In a bolster, head-blocks composed of sections separable laterally, each of which sections is provided with a recess, a tension member with enlarged end portion, and a compression member coöperating therewith adapted to prevent lateral separation of said sections; substantially as described.
- 25 19. In a bolster, head-blocks divided vertically and provided with seats, tension members supported in said seats, and a compression member adapted to prevent lateral separation of the parts of said head-blocks; substantially as described.
- 30 20. In a bolster, a compression member, a tension member, a plurality of head-block sections and laterally-extended recesses in each section adapted to hold enlarged ends of a tension member therein; substantially as described.
- 35 21. In a bolster, a compression member, a tension member, and head-blocks composed of parts separately formed adapted to secure an imperforate tension member in position; substantially as described.
- 40 22. In a bolster, an imperforate tension member, a compression member, and head-blocks comprising sections separately formed and which are adapted to hold in operative position said imperforate tension member; substantially as described.
- 45 23. In a bolster, separable head-blocks provided with laterally-extending seats, an imperforate tension member, with enlarged ends supported therein, a channel compression member, a strut, and means extended laterally through said compression member and said head-blocks adapted to hold them together; substantially as described.
- 50 24. In a bolster, separable head-blocks, and a spring-seat provided with means for holding said head-block members together substantially as described.
- 55 25. In a bolster, sectional head-blocks, and a spring-seat provided with flanges integral therewith adapted to hold said head-block sections together; substantially as described.
- 60 26. A bolster provided with head-blocks which are separable laterally, and a compression member connected therewith by means extending laterally through said head-blocks; substantially as described.
- 65 27. A bolster provided with laterally-separable head-blocks, a tension member with enlarged end portions supported therein, a strut, a compression member and ties connecting said tension member and said compression member, between said head-blocks and said strut; substantially as described.
- 70 28. In a bolster, an imperforate tension member with enlarged ends, separable head-block sections provided with seats for said enlarged ends, a compression member, and means for holding said head-block sections together; substantially as described.
- 75 29. In a bolster, an imperforate tension member with enlarged ends, separable head-block sections provided with seats for said enlarged ends, a compression member, and means separate therefrom for holding said head-block sections together; substantially as described.
- 80 30. In a bolster, an imperforate tension member, with enlarged ends, separable head-block sections provided with seats for said enlarged ends, a compression member, and means integral therewith for holding said head-block sections together; substantially as described.
- 85 31. In a bolster, an imperforate tension member with enlarged ends, separable head-block sections provided with seats for said enlarged ends, a channel compression member, and means for holding said head-block sections together; substantially as described.
- 90 32. In a bolster, laterally-separable head-blocks provided with seats therein, a tension member with enlarged end portions in said seats, a compression member, and a strut; substantially as described.
- 95 33. In a bolster, laterally-separable head-blocks provided with seats therein, an imperforate tension member with enlarged end portions in said seats, a compression member and a strut; substantially as described.
- 100 34. In a bolster, a compression member, an imperforate tension member, a strut, and sectional head-blocks so formed that when the said parts are arranged in operative position they are held together without the aid of additional securing means; substantially as described.
- 105 35. In a bolster, a plurality of separable head-blocks, a tension member coöperating therewith, which tension member is provided with enlarged ends, and a compression member adapted to hold the head-block sections together; substantially as described.
- 110 36. In a bolster, a plurality of laterally-separable head-blocks, a tension member coöp-

erating therewith; which tension member is provided with enlarged ends, and a compression member adapted to hold the head-block sections together; substantially as described.

5 37. In a bolster, a compression member and laterally-separable head-block sections adapted to be locked together and upon a tension member by means of said compression member; substantially as described.

10 38. In a bolster, a plurality of cast-metal head-blocks comprising laterally-separable sections, and a tension member with enlarged ends supported therein; substantially as described.

15 39. A bolster comprising a plurality of members which are separately formed and which has an imperforate tension member, and head-block sections locked to said tension member by means passing laterally therethrough; substantially as described.

20 40. In a bolster, head-blocks divided substantially vertically and longitudinally of said bolster; substantially as described.

25 41. In a bolster, head-blocks divided substantially vertically and longitudinally of said bolster and which are separable laterally to permit introduction of the ends of a tension member therein; substantially as described.

30 42. In a bolster, head-blocks divided substantially vertically and longitudinally of said bolster and which are separable laterally

to permit introduction of the ends of a tension member with enlarged end portions therein; substantially as described.

35 43. In a bolster, a sectional head-block so formed as to securely lock the tension member of said bolster therein, both of said members being devoid of perforations at the interlocking coupling thereof; substantially as described.

40 44. In a truss-bolster, a compression member, a tension member, a strut, and head-blocks formed in detached sections which are divided vertically and separable laterally; substantially as described.

45 45. In a bolster, a flanged compression member, in combination with bolster head-blocks formed of detached sections which are provided with recesses adapted to embrace the ends of a tension member, and a tension member coöperating therewith, which is so formed as to be held in position, to resist longitudinal strain on said tension member, by less than a full quota of said sections; substantially as described.

50 In testimony whereof I hereunto affix my signature, in the presence of two witnesses, this 21st day of April, 1903.

WILLIAM H. SCOTT.
